U.S. Cl. D54—12

FIG. 1

FIG. 2

FIG. 3

FIG. 4

FIG. 5

FIG. 1 is a front end view of a fork or similar article embodying my novel design;

FIG. 2 is a top plan view thereof;

FIG. 3 is a side elevational view thereof;

FIG. 4 is a bottom plan view thereof;

FIG. 5 is a rear end view thereof;

The essential features of my design for a fork or similar article reside in the configuration of the handle in combination with the particular type of ornamentation as applied thereto.

The design is intended for use on sets comprising forks, spoons, knives and similar articles of flatware.

I claim:

The ornamental design for a fork or similar article, as shown and described.
